DESIGN FOR A GRIP FOR HAMMER HANDLES AND LIKE ARTICLES

Herbert Harvey, Pekin, Ill., assignor to Chester
G. Hellyer, Pekin, Ill.

Application May 31, 1941, Serial No. 101,244

Term of patent 14 years

To all whom it may concern:

Be it known that I, Herbert Harvey, a citizen of the United States, residing at Pekin, in the county of Tazewell, State of Illinois, have invented a new, original, and ornamental Design for a Grip for Hammer Handles and like articles, of which the following specification, reference being had to the accompanying drawing, forming part hereof.

Figure 1 is a view in perspective of the grip for hammer handles and like articles, showing my design.

Figure 2 is a top plan view.

Figure 3 is a side elevation of the grip as seen in its longest diameter.

Figure 4 is a side elevation of the grip as seen in its shortest diameter, and

Figures 5 and 6 are sectional elevations of the grip corresponding to Figures 3 and 4, respectively.

The characteristic feature of the device of this

invention includes the location on an otherwise relatively smooth surface of the flexible gripping member, oval as viewed endwise, of outwardly projecting ribs, one located at each side of the member at the narrowest portion and one located at each side of the member at the point of greatest length as the article is viewed endwise, the end portions of all of the ribs extending in curved configuration from the side wall partially over the end surface, the ends of the ribs terminating in spaced relation to each other. The article is further characterized by the contour of the extreme end of the oval shaped element in that the end surface is flat except for the spaced ends of the ribs which project up above the flat surface.

I claim:

The ornamental design for a grip for hammer handles and like articles, as shown and described.

HERBERT HARVEY.
